UNITED STATES PATENT OFFICE.

JOHN N. HELTZEL, OF WARREN, OHIO.

CONCRETE SURFACING JOINT AND MEANS FOR AND METHOD OF FORMING THE SAME.

Application filed January 22, 1925. Serial No. 3,972.

The present invention relates to concrete surfacing structures, such as roads, pavements, platforms, floors, and the like, and aims to provide novel and improved joints therefor and novel and improved means for and method of producing such joints, whereby the road or other surfacing structure is divided in a predetermined manner into sections or slabs.

It is well known that a concrete road (or similar surfacing structure) will, on account of contraction and expansion with changes of temperature and on account of the heaving and sinking of the ground or sub-base, crack or divide along irregular lines and at irregular intervals, when the road is built solid. The irregular breaking of the concrete is not only unsightly, but it frequently results in the disintegration of the road to a very marked degree due to the breaking off or ravelling of the concrete along the breaks or cracks. This makes the maintenance cost of the road excessive, and also shortens the life of the road. Artificial longitudinal joints are being used to some extent and with a degree of satisfactory results, although they are somewhat expensive to install as heretofore carried out. However, the practice of installing artificial transverse joints has been practically abandoned, chiefly on account of the almost physical impossibility of installing such transverse joints properly. Hence, it is the prevailing practice to allow the transverse joints or divisions to develop at random, causing irregular cracks across the road resulting from the contraction of the concrete structure after its final set.

The present invention contemplates the convenient and economical production of both longitudinal and transverse joints in the road or concrete surfacing structure, whereby the joints or divisions and sections or slabs defined thereby are uniform and straight. The concrete is divided along definite or straight lines for a desired depth below its upper surface, so that rectangular or other desired shapes of slabs or sections are defined, with the cracks or breaks between such sections or slabs located below the divisions, thereby obtaining straight line divisions at the upper surface of the concrete and breaks below the surface so that the adjacent sides or edge portions of the sections or slabs are flexibly interengaged, due to the irregular

breaking of the concrete, to prevent the sections from being displaced vertically relatively to one another at the joints, but permitting the sections to have a slight flexing movement relatively to one another, such as when the sub-base or ground heaves or sinks owing to climatic changes or heavy loads. The joints thus present straight and regular lines at the upper surface of the concrete, so that the slabs or sections are of predetermined shape, and the sections or slabs are poured solid or continuous. The breaking or cracking of the concrete, when hardened or finally set, occurs below the divisions made, so that no irregular cracks appear at the upper surface of the concrete, and so that the cracking of the concrete at the joints will result in the adjacent sides or edges of the sections or slabs fitting together flexibly and in such a manner, owing to the irregular breaking of the concrete, to prevent the sections from being displaced vertically relatively to one another. Therefore, the upper surfaces of the sections will remain flush with one another, even though the road may be raised or lowered with the sub-base or ground.

It is also an object of the invention to form the joints after the concrete or grout has been poured, so as to eliminate the necessity for placing forms or joint members on the sub-base or ground previous to pouring the concrete, thereby saving time and eliminating interference with pouring, and, furthermore, the joints can be made along regular lines with uniformity and precision.

With this invention the longitudinal joint of the road may also define or combine therewith a traffic line for the purpose of dividing traffic moving in opposite directions.

With the foregoing and other objects in view, which will be apparent as the invention is more fully understood, the invention resides in the novel features as hereinafter pointed out and claimed, it being understood that changes can be made within the scope of what is claimed without departing from the spirit of the invention.

The invention is illustrated in the accompanying drawings, wherein—

Figure 1 is a perspective view depicting the first step in forming one species of joint, with the mandrel blade above the joint forming strip or sheet.

being forced down into the concrete by the mandrel blade.

Fig. 3 is a cross section showing the strip completely forced down into the concrete.

5 Fig. 4 is a cross section showing the completed joint.

Fig. 5 is a perspective view corresponding with Fig. 1 illustrating the first step in the production of a joint of another species, 10 using a pre-formed joint member or form.

Fig. 6 is a cross section showing the joint member or form forced down into the concrete.

Fig. 7 is a cross section showing the mandrel blade removed and a cap and spreader bar or member inserted in the joint member.

Fig. 8 is a cross section showing the completed joint.

Fig. 9 is a fragmentary plan view of the road constructed, using the joint shown in Fig. 4 for the transverse joints, and the joint of Fig. 8 for the longitudinal joint and traffic line.

25 Figs. 10, 11 and 12 are cross-sections corresponding with Figs. 6, 7 and 8 illustrating a modification wherein the upper portion of the joint is widened to provide a broad traffic line.

30 Figs. 13, 14 and 15 are cross sections corresponding with Figs. 6, 7 and 8 illustrating another modification.

Fig. 16 is a perspective view showing an appliance for producing, in a different way, the joint shown in Fig. 4.

35 Fig. 17 is a cross section of said appliance illustrating the first step in the method of producing the joint.

Fig. 18 is a similar cross section showing the strip or sheet being forced down and folded preparatory to entering the concrete.

Fig. 19 is a similar cross section showing the strip forced down into the concrete.

Fig. 20 is a perspective view similar to Fig. 16 illustrating a modified form of appliance, and Figs. 21, 22 and 23 are cross sections corresponding with Figs. 17, 18 and 19 showing the steps in the formation of the joint.

Fig. 24 is a cross section of other modified means for producing a combined joint and traffic line, and Fig. 25 is a cross section of the completed joint and traffic line as formed thereby.

Fig. 26 is a cross section showing still another means for obtaining a combined joint and traffic line, and Fig. 27 is a cross section of the completed joint and traffic line.

Referring to Figs. 1, 2, 3 and 4, the appliance or means used to form the joint comprises a mandrel blade 21 of suitable length and depth, having the outstanding flanges 22 at its opposite sides, preferably formed by securing angle irons to the upper edge portion of the blade. The blade extends a suitable distance below the flanges 22, depending on the depth of the division desired.

in the concrete. In practice, with a concrete road of six to nine inches in thickness, the blade 21 extends about three inches below the flanges 22 so as to cut substantially one-half way through the concrete or less.

In carrying out the method, a strip or sheet 23 of water-proof paper, fabric, rubber, sheet metal, or other suitable easily-bendable material, is placed on the surface of the plastic concrete 20 over the line where the joint is to be formed. The blade 21, which may be manipulated by hand or operated by suitable machine, such as disclosed in my copending application Serial No. 6,806, filed Feb. 4, 1925, is positioned above the strip 23 over the line of the joint to be formed, with the edges of the strip 23 spaced equal distances to opposite sides of such line and the blade. The blade 21 is then forced down, preferably with a vibratory or jarring action, so as to force the blade down into the concrete. The lower edge of the blade contacts with the strip 23 along the longitudinal median line of the strip, thereby forcing the strip down into the concrete, and folding the opposite wings or edge portions of the strip upwardly against the opposite sides of the blade, as seen in Fig. 2. The strip is thus automatically folded

The strip is pushed into the concrete along its longitudinal center line with its edges directed upwardly, and the folded strip is shoved down into the concrete with and on the mandrel. The strip should be of material that will bend or fold together when pushed down into the plastic concrete by the blade, 95

the pressure of the plastic material against the opposite wings of the strip, when the strip is pushed down into the concrete, folding the strip against the blade. Any stones, gravel or other solid pieces in the grout lying in the

path of the blade 21 will be deflected to one side or the other as the blade is forced down, and the vibratory or jarring action of the blade will facilitate its entry into the concrete. The flanges 22 in reaching and coming

into contact with the surface of the concrete, as seen in Fig. 3, will limit the depression of the mandrel blade into the concrete, and, furthermore, said flanges will serve to level off and tamp the surface of the concrete at the

oil and tamp the surface of the concrete at the opposite sides of the division, so as to smooth down any irregularities that may have been formed by pushing the strip or joint member 23 into the concrete. This part of the formation of the joint is done after the surface of

tion of the joint is done after the surface of the concrete has been struck off and before the surface is finished. The blade 21 is then lifted and removed from the road, so as to be withdrawn from the joint. The strip or member 22 follows at its outer surface to the

member 23 adheres at its outer surfaces to the plastic concrete, so as to remain in the concrete, while the friction between the strip and blade is much less, thereby permitting the blade to be withdrawn from the strip without the strip being lifted or torn from the concrete. As soon as the blade is withdrawn

from the strip 23, the pressure of the concrete against the opposite sides of the strip will press the wings or sides of the strip together, as seen in Fig. 4, thereby closing the crevice or slot previously occupied by the blade, and bringing the wings or sides of the strip snugly together. The surface of the concrete is then finished, and this can be done over the joint without interference. The joint is finished by a jointing tool, which rounds the corners of the concrete along the edges of the joint, to prevent the edges from ravelling or breaking off.

After the concrete has hardened, the contraction thereof will cause the concrete to break or crack, as at 24, below the strip or joint member 23, thereby dividing the concrete into sections or slabs of predetermined shape, according to the arrangement of the joints. The break or fracture 24 below the doubled strip or joint member will be irregular, although it will not extend to the surface of the concrete. However, the irregularity of the break 24 will result in the adjacent sections or slabs being fitted together with a dowel effect to prevent the sections from being displaced vertically relatively to one another, although providing a flexible joint to permit said sections to flex, with a hinging action, relatively to one another, such as when the sub-base heaves or falls. It is natural that the concrete being weakened along the line of the strip or joint member 23 will break along such line, rather than forming irregular breaks or cracks along other lines. The wings or sides of the strip 23 adhering to the concrete and failing to adhere to one another will maintain the division or separation of the concrete where said strip or joint member is inserted. The strip 23 is preferably of thin material, so as to produce a hair-line crack or joint that will not be unsightly and which will be practically invisible excepting when the joint opens due to the contraction of the concrete. The strip or joint member 23 may also extend less or more than one-half of the distance through the concrete, as may be desired or necessary, and may extend only one-third or one-fourth of the way down into the concrete with the same results. When the strip or joint member is forced down into the concrete the concrete is simultaneously cut down from its surface the corresponding distance, to define the sections or slabs. It is preferable, when forcing the strip 23 into the concrete, to push the strip down sufficiently so that its edges are about one-eighth of an inch below the surface of the concrete, thereby permitting the surface to be finished off without the interference of the strip or joint member. The action of the flanges 22 will also tamp or press down any high or raised portions along the opposite sides of the cut made in the concrete. The several steps are accomplished quickly

and conveniently, with little time and expense, and the joint will be straight and accurate.

Figs. 5, 6, 7 and 8 illustrate a modified method for obtaining a modified form of joint. The same or similar mandrel blade 21 is used, and the joint member or form 23^a is pre-formed, being composed of a strip of sheet metal doubled along its longitudinal center line so that the member or form 23^a is a V-shaped cross section. The member or strip 23^a serves as a form to define a slot or groove in the concrete.

In carrying out the method, the member or form 23^a is positioned along the desired line 80 on the concrete 20, and the blade 21 is positioned in said member 23^a to bear at its lower edge in the bend of said member. The blade, with the member 23^a thereon, is then forced down into the concrete with a vibratory or jarring action, while the concrete is still soft, the surface of the concrete having been struck off. The member or form 23^a is thus forced down into the concrete, thereby producing the cut or division in the concrete extending to the desired depth below the surface. The flanges 22 will press or level down any raised portions or high spots in the surface of the concrete along the opposite edges of the cut made, and the member or form 23^a is thus positioned in the concrete along a definite line. The blade 21 is then raised and removed, leaving the member or form 23^a in place. A cap and spreader bar or member 25 is then inserted between the wings or sides of the member 23^a, as seen in Fig. 7, and is preferably flush with the upper edges of said member. The surface of the concrete is then finished off, and the edges of the concrete are rounded off along the groove formed by the member 23^a, the bar or member 25 preventing the concrete from dropping down into the member 23^a, as well as keeping the sides or wings of said member spread apart. After the concrete has set, the bar 25 is removed from the member or form 23^a, after which the form or member 23 is removed from the concrete, the removal of said member from the concrete being facilitated by springing the wings or sides of said member toward one another. This leaves a V-shaped groove or slot 26 in the concrete, and the subsequent contraction of the concrete will result in the fracture or break 24^a occurring below said groove 26, as seen in Fig. 8. The groove 26 is filled with tar macadam or other plastic composition, as at 27, to seal the joint, and to also provide a traffic line. The joint is flexible to permit the sections or slabs of concrete to flex relatively to one another, but the irregular form of the fracture or crack 24^a will lock the sections against relative vertical displacement. In this type of joint, the doubled joint member or form 23^a does not remain in

the concrete, but is removed to provide a groove or space for the sealing and traffic line member 27.

Fig. 9 illustrates the use of the two species of joints hereinbefore described in a road construction. Thus, the first described joints are used transversely of the road at suitable intervals, about fifty feet apart in practice, and the second described joint is used along the center line of the road to produce a longitudinal division joint and traffic line. The strips or joint members 23 extend from the longitudinal joint and traffic line to the opposite edges of the road, while the longitudinal center joint and traffic line may be continuous.

Both the transverse as well as the longitudinal joints may be made by machine, as well as by hand, such a machine being disclosed in the copending application hereinbefore referred to, and in forming both joints it is preferable to vibrate or jar the mandrels when forcing them down into the concrete. The perfect alinement of the transverse and longitudinal joints may be obtained, at low cost. The longitudinal joint and traffic line, it will be apparent, is formed by forcing one member or form 23^a after the other in succession into the concrete following the machine which pours the concrete on the sub-base, the members or forms 23^a being ten feet long and being positioned end to end as the road progresses. Said members 23^a are used repeatedly, being removed from the road after the concrete has set sufficiently, as hereinbefore described.

In the modification shown in Figs. 10, 11 and 12, the mandrel 21^b has the opposite side flanges 22^b, and the doubled joint member 40 or form 23^b has its edge portions offset, as at 28, away from one another. Said member or form 23^b is thrust down into the concrete, and after the mandrel is removed, a cap and spreader strip 25^b is positioned in the mouth 45 of the form or member 23^b within and between the offset portions 28, thereby keeping the sides or wings of the form 23^b spread apart and also closing said form to keep out concrete therefrom. After the concrete has 50 set sufficiently, the strip 25^b is removed, and the form 23^b is then withdrawn from the concrete, the sides or wings thereof springing toward one another to facilitate removal. This leaves the groove 26^b in the concrete 55 with a wide or broad channel 29 at the surface of the concrete, and said groove and channel are filled with a suitable composition 27^b to form the joint seal and traffic line, such traffic line being broader than the one 60 shown in Fig. 8 on account of the widening of the cut made in the concrete.

Figs. 13, 14 and 15 illustrate another modification in which the mandrel 21^c has a single flange 22^c, and the form 23^c has one side or 65 wing flat and has the offset 28^c at the upper

edge of its other side or wing. After the form has been forced down into the concrete and the mandrel is removed, a cap and spreader strip 25^c is positioned between the upper edges of the form. Said strip and form are removed in succession after the concrete has hardened, thereby providing the groove 26^c and broad channel 29^c. In this construction the groove 26^c is below one edge of the channel, so that concrete may be used for the seal and traffic line 27^c, it being noted that the crack 24 in the concrete will be below one side of the seal and traffic line 27^c so as not to fracture same. If the sections or slabs separate up to the surface of the concrete, such separation will occur between the seal and traffic line 27^c and the section or slab at the left thereof in Fig. 15.

Figs. 16, 17, 18 and 19 illustrate a modified form of appliance for producing the joint shown in Fig. 4. The mandrel blade 21^d is movable downwardly between a pair of parallel guide bars or members 30 when thrust downwardly to enter the concrete. Said bars 30 have depending flanges 31, the lower edges of which are sharp in order to slightly enter the concrete along the opposite sides of the line of the joint, the bars 30 being supported by hand or by machine or other mechanical means. Arches 32 are secured to the bars 30 and have upstanding slotted guides 33 in which the mandrel blade 21^d is disposed when raised, and the blade 21^d has suitable means for depressing and raising it. As shown, the blade 21^d has the upstanding arms 34.

In using the appliance it is positioned over the concrete along the desired line, with the edges of the flanges 31 entering the concrete tightly. The strip 22^d is then positioned on the bars 30, and may be slid lengthwise on said bars under the mandrel blade which is in raised position. The mandrel blade is then moved downwardly, thereby forcing the central portion of the sheet or strip 23^d down into the slot between the bars 30, and folding the strip to bring the opposite wings or sides thereof against the sides of the blade. The strip is thus folded or doubled before entering the concrete, and the blade moving downwardly will force the strip into the concrete, as seen in Fig. 19, after which the blade is raised to retract it from the strip 23^d. The appliance is then removed from the concrete. By using the bars 30 the strip is folded thereby, and this will reduce the agitation of the concrete at the joint, assisted by the flanges 31 between which the strip enters the concrete. The joint produced will be the same as shown in Fig. 4, the edges of the flanges 31 assisting in beveling the edges of the concrete along the joint.

Figs. 20, 21, 22 and 23 illustrate a modification of the appliance shown in Figs. 16-19. The bars 30^e have the flanges 31^e and are connected by upstanding slotted guides 130

33° in which the mandrel blade 21° is positioned. As shown in Fig. 21, the strip 23° is placed on the bars 30° under the raised blade 21°. Said blade is then forced downwardly 5 to fold the strip and force it downwardly between the flanges 31° into the concrete. The blade 21° is forced downwardly by means of one or more implements 33 that are used to receive the blows of a hammer or other driving implement, said implements 35 passing downwardly between the bars 30°, as seen in Fig. 23. The bars 30° can then be removed from the concrete, leaving the blade 21° in the strip 23° if desired, so that the blade or 10 bar 21° will form a part of the completed joint, or said blade may be removed subsequently when an open joint is desired.

Fig. 24 shows a mandrel blade 21° secured to one edge of a form bar 22°, and the blade 20 21° is used for forcing down a doubled strip or sheet 23° into the concrete. The bar 22° forms a channel 29° in the concrete at the surface thereof at one side of the joint, and when the bar 22° and blade 21° are withdrawn, the wings or sides of the strip 23° are pushed together. One edge of the strip is flush with the bottom of the channel 29° while the other edge extends to or near the surface of the concrete, the corresponding 25 wing or side of the strip extending along one wall of the channel. The channel is then filled with concrete or other plastic material 27°, which hardens, to form a broad traffic line located entirely at one side of the joint, so that said traffic line will not be broken 30 by the separation of the sections or slabs defined by the joint.

Fig. 26 shows the use of a mandrel 21° of T-shaped cross section. The doubled paper 40 or similar strip 23° is pushed down into the concrete below the flanges 22° of the mandrel, and said flanges are pressed down into the concrete to form a broad channel 29°. When the mandrel is removed, leaving the 45 strip 23° in the concrete, the wings or sides of said strip are pressed together by the concrete. The channel 29° is then filled with a suitable flexible or yieldable composition, such as tar, macadam, or the like, to form 50 the traffic line 27° (Fig. 27) extending over and across the joint, said traffic line being of flexible or yieldable material will not break above the joint, although the joint may open below said traffic line.

55 When using the mandrels and channel producing members shown in Figs. 24 and 26, after the mandrels and channel forming members are removed from the concrete, the channels are preserved by placing suitable 60 forms or bars therein, although the concrete presses the sides of the strips 23° and 23° together. Such forms or bars are removed after the concrete has set sufficiently so that the channels can be filled with the materials 65 forming the traffic lines.

It is also possible to use the process and mandrel or cutter blade with a plastic composition for producing the joint. Thus, by applying a suitable plastic composition or semi-solid material to the sides of the blade, 70 such composition or material may be forced down into the plastic concrete to produce the division in the concrete structure. Such composition or material should be such that it will not adhere to the blade if it is intended 75 that the blade shall be removed, although, in some instances the blade may be left in the road structure. Thus, by depositing the composition or material in the plastic concrete, and using such material as will not 80 produce a bond in the cut or incision made, the concrete will remain divided, and after becoming solid will crack below the strip of composition or material and incision or cut containing the same.

Having thus described the invention, what I claimed as new is:—

1. A joint of a concrete surfacing structure comprising a doubled strip embedded in the concrete, with its sides bearing together 90 from the bend to the edges and its edges near the surface of the concrete.

2. A joint of a concrete surfacing structure comprising a doubled strip embedded in the concrete with its edges near the surface of the concrete, the concrete having a channel therein extending along the edges of said strip and wider than the width of said doubled strip, and material in said channel forming a traffic line.

3. A joint of a concrete surfacing structure comprising a doubled strip embedded in the concrete with its sides bearing together and its edges near the surface of the concrete, the concrete having a channel in its surface 105 extending along the edges of said strip, and material filling said channel and forming a traffic line.

4. A joint of a concrete surfacing structure comprising a doubled strip embedded in the concrete with its bend below the surface and above the bottom of the concrete and with its edges near the surface of the concrete, the concrete having a channel in its surface extending along the edges of said strip and wider than the width of the doubled strip, and material in said channel forming a traffic line.

5. A joint of a concrete surfacing structure comprising a doubled strip embedded in the concrete with its bend below the surface and above the bottom of the concrete and with its edges near the surface of the concrete, the sides of the strip bearing together, the concrete having a channel in its surface extending along the edges of said strip, and material in said channel forming a traffic line.

6. The method of producing a joint in a concrete surfacing structure consisting in forcing a doubled strip down, bend lower.

most, into the concrete after the concrete is in place and while it is plastic to divide the concrete.

7. The method of producing a joint in a concrete surfacing structure consisting in forcing a doubled strip down, bend lowermost, into the concrete after the concrete is in place and while it is plastic and depositing the strip in the concrete with its edges near 10 the surface of the concrete.

8. The method of producing a joint in a concrete surfacing structure consisting in forcing a blade, with a doubled strip thereon, down into the concrete after the concrete is 15 in place and while it is plastic to divide the concrete, and withdrawing the blade to deposit the strip in the concrete.

9. The method of producing a joint in a concrete surfacing structure consisting in 20 forcing a blade down into the concrete while plastic to divide the concrete, with a doubled strip on the blade having its bend below the lower edge of the blade and its sides at opposite sides of the blade, and then withdrawing 25 the blade to deposit the strip in the concrete.

10. The method of producing a joint in a concrete surfacing structure consisting in forcing down into the concrete while plastic the intermediate portion of a bendable strip 30 to double the strip and force it, bend lowermost, into the concrete.

11. The method of producing a joint in a concrete surfacing structure consisting in 35 positioning a bendable strip above the concrete while plastic and forcing the intermediate portion of the strip down foremost with a blade, to double the strip on the blade and force the strip, bend lowermost, into the concrete.

12. The method of producing a joint in a concrete surfacing structure consisting in forcing down into the concrete while plastic the intermediate portion of a bendable strip with a blade, to double the strip on the blade 45 and force the strip, bend lowermost, into the concrete, and then withdrawing the blade to permit the concrete to press the sides of the strip together.

13. The method of producing a joint in a concrete surfacing structure consisting in substantially simultaneously doubling a strip 50 and forcing it, bend lowermost, down into the concrete after the concrete has been put in place and while it is still plastic.

14. The method of producing a joint in a concrete surfacing structure consisting, with a single operation, in doubling a strip and forcing it, bend lowermost, down into the concrete after the concrete has been put in 60 place and while it is still plastic.

15. The method of producing a joint in a concrete surfacing structure consisting in forcing a strip down into the concrete while plastic with a blade so as to double the strip

on the blade and force the doubled strip, bend 65 lowermost, with a single operation into the concrete.

16. The method of producing a joint in a concrete surfacing structure consisting in forcing a blade, with material thereon, down 70 into the concrete after the concrete is in place and while it is plastic to divide the concrete, and withdrawing the blade to deposit the material in the concrete.

17. The method of producing a joint in a concrete surfacing structure consisting in forcing a blade, with material on opposite sides thereof, down into the concrete after the concrete is in place and while it is plastic to divide the concrete, and withdrawing the 80 blade to deposit the material in the concrete.

18. Means for producing a joint in a concrete surfacing structure while the concrete is plastic, including a mandrel blade to be forced down into the plastic concrete and 85 having portions at opposite sides to come into contact with the surface of the concrete, and a doubled strip on said blade with its bend under the lower edge of the blade and its edges below said portions.

19. Means for producing a joint in a concrete surfacing structure while the concrete is plastic, including a mandrel blade to be forced down into the plastic concrete and having opposite side flanges to come into contact with the surface of the concrete, and a doubled strip on the blade with its bend under the lower edge of the blade and its edges at the opposite sides of the blade below said flanges.

20. The method of producing a joint in a concrete surfacing structure consisting in forcing a strip down into the concrete after the concrete is in place and while it is plastic and depositing said strip in the concrete 100 completely below the surface of the concrete.

21. The method of producing a joint in a concrete surfacing structure consisting in forcing a blade with a strip thereon down into the concrete after the concrete is in place and while it is plastic to bring the strip completely below the surface of the concrete and to divide the concrete, and withdrawing the blade to deposit the strip in the concrete.

22. The method of producing a joint in a concrete surfacing structure consisting in producing a cut in the concrete after the concrete is in place and while it is still plastic, and depositing material in the cut completely below the surface of the concrete.

23. The method of producing a joint in a concrete surfacing structure consisting in producing in the concrete, after the concrete is in place and while it is still plastic, a cut extending from the upper surface of the concrete to a substantial depth and spaced above 125 the sub-base of the concrete, and depositing material in said cut completely below the surface of the concrete with the concrete united

below said cut while the concrete is plastic and free to break when the concrete has hardened.

24. The method of producing a joint in a concrete surfacing structure consisting in producing a cut in the concrete after the concrete is in place and while it is still plastic, and depositing a strip in said cut completely below the surface of the concrete.

10 25. The method of controlling the longitudinal and transverse breaks of a concrete road consisting in producing longitudinal and transverse cuts in the surface of the concrete after the concrete is in place and while it is still plastic and depositing material in said cuts completely below the surface of the concrete to divide the concrete into slabs.

20 26. The method of producing a joint in a concrete surfacing structure consisting in moving a blade in the plastic concrete to produce a separation of the concrete, and using said blade to deposit joint producing material in the concrete.

25 27. The method of producing a joint in a concrete surfacing structure consisting in moving a blade in the plastic concrete to produce a separation of the concrete, and using said blade to deposit a strip in said separation of the concrete.

30 28. The method of producing a joint in a concrete surfacing structure consisting in

moving a blade in the plastic concrete to produce a separation of the concrete in combination with joint producing material associated with said blade so that said material 35 is deposited in said separation produced in the concrete.

29. The method of producing a joint in a concrete surfacing structure consisting in moving a blade in the plastic concrete to 40 produce separation of the concrete, with a strip associated with the blade, so that said strip is deposited in said separation produced in the concrete.

30. The method of producing a joint in a 45 concrete surfacing structure consisting in supplying joint producing material to a blade and moving the blade in the plastic concrete to produce a separation of the concrete, to deposit the material in said separation, and 50 to remove the blade from said deposited material.

31. The method of producing a joint in a concrete surfacing structure consisting in supplying a strip to a blade and moving the 55 blade in the plastic concrete to produce a separation of the concrete, to deposit said strip in said separation and to remove the blade from said strip.

In testimony whereof I hereunto affix my 60 signature.

JOHN N. HELTZEL.
